SLIDE BUCKLE

Jerome R. La Vigne, Waterbury, Conn., assignor
to The Waterbury Buckle Company, Water-
bury, Conn., a corporation of Connecticut

Application June 5, 1940, Serial No. 338,864

2 Claims. (Cl. 24—196)

The present invention relates to improvements in buckles and more particularly to improvements in slide-buckles of the general type where in one member slides with respect to another member to grip a strap or the like.

One of the objects of the present invention is to provide a superior slide-buckle so constructed and arranged as to be assemblable with ease and rapidity.

Another object of the present invention is to provide a superior slide-buckle comprising two coacting members and so constructed and arranged that a strap or the like may be securely attached to one of the said members while the same is conveniently available and prior to the assembly of such member with the other of said members.

A further object of the present invention is to provide a superior slide-buckle so constructed and arranged as to combine effectiveness of holding power with low cost of manufacture.

With the above and other objects in view, as will appear to those skilled in the art from the present disclosure, this invention includes all features in the said disclosure which are novel over the prior art and which are not claimed in any separate application.

In the accompanying drawing, in which certain modes of carrying out the present invention are shown for illustrative purposes:

Fig. 1 is a view in front elevation of a slide-buckle embodying the present invention, and shown as organized with a strap and a button-loop which are partly broken away;

Fig. 2 is an edge view thereof;

Fig. 3 is a rear view thereof;

Fig. 4 is a view in longitudinal section taken on the line 4—4 of Fig. 1 but on a larger scale;

Fig. 5 is a transverse sectional view taken on the line 5—5 of Fig. 1, but on a larger scale;

Fig. 6 is a perspective view of the body-member, detached; and

Fig. 7 is a perspective view of the gripping-member, detached.

The particular slide-buckle herein chosen for purposes of illustrating the present invention includes a body-member or frame generally designated by the reference character 10, and a gripping-member generally designated by the reference character 11 and having relative sliding movement lengthwise of the said body-member.

The body-member 10 above referred to, is preferably stamped up from sheet metal, and includes a substantially-flat front-panel 12, from

the respective side-edges of which rearwardly project longitudinally-extending side-walls 13—13. The said side-walls 13—13 terminate about midway the length of the body-member 10 and the rear edge of each thereof slopes rearwardly away from the front-panel 12 and downwardly toward the outer or lower end of the body-member to provide each of the said side-walls with a rearwardly-facing inclined camming-surface 14.

Adjacent its lower end the front-panel 12 of the body-member 10 is provided with a series of transversely-extending flutes 15 to provide a gripping surface for the retention of a strap, in a manner as will hereinafter appear. Adjacent its upper end the body-member 10 is formed with a transversely-extending slot 16, the respective opposite end-walls of which project beyond the outer faces of the side-walls 13—13 of the said body-member to provide laterally-extending stop-ears 17—17 for limiting the movement of the gripping-member 11, in a manner as will hereinafter appear. Intermediate the upper ends of its side-walls 13—13 and its stop-ears 17—17, the body-member 10 is contracted in width by the formation of one of two notches 18—18 in each of the respective opposite sides of the said body-member.

The gripping-member 11 before referred to, 30 comprises a front gripping-bar 19 extending transversely across the front face of the front-panel 12 of the body-member 10, and a rear strap-attaching bar 20 extending transversely across the rear of the body-member 10 substantially parallel to the said gripping-bar 19. The gripping-bar 19 and the strap-attaching bar 20 are united at their respective opposite ends by integral relatively-short end-bars 21—21, as is particularly well shown in Fig. 7. As 35 thus constructed, the gripping-member 11 may if desired be conveniently formed from relatively-heavy wire to provide an elongated structure of closed rectangular form and of adequate strength. Each of the end-bars 21—21 extends rearwardly along the outer face of the adjacent one of the two side-walls 13—13 of the body-member 10. The portions of the strap-attaching bar 20 adjacent each of the said end-bars 21—21 provide forwardly-facing cam-surfaces 40 22—22 for engagement respectively with the adjacent one of the camming-surfaces 14—14 of the side-walls 13—13.

The slide-buckle may be assembled in a variety of manners but preferably the so-called "fixed-portion" 23 of a strap, such for instance,

as a strap 24, is wrapped around the strap-attaching bar 20 of the gripping-member 11 and sewn or otherwise secured in place as is particularly well shown in Fig. 4 and preferably prior to the assembly of the said gripping-member with the body-member 10.

The gripping-member 11 may be threaded over the upper end of the body-member 10 which threading operation is facilitated by the notches 18-18 in the respective opposite sides of the said body-member inasmuch as the said notches permit the "maneuvering," so to speak, of the gripping-member 11 over the upper end of the body-member 10 which is wider than the internal width of the said gripping-member.

The free- or running-portion 25 of the strap 24 may now be extended around the suspension-bar 26 of a button-loop 27 or the like. The said button-loop 27 may be "hooked," so to speak, over a button of a garment such, for instance, as the button commonly employed upon the bibs of overalls. The running-portion 25 of the strap 24 may now be slipped in between the front-panel 12 of the body-member 10 and the rear face of the gripping-bar 19 of the gripping-member 11. The said running-portion 25 is preferably then passed rearwardly through the slot 16 in the upper end of the body-member 10 and thence led upwardly for attachment to whatever portion of the garment is desired.

During the operation of inserting the running-portion 25 of the strap 24 as above described, the gripping-member 11 will, if not already so positioned, be moved upwardly toward the slot 16 to thus provide ample space for the insertion referred to.

It may here be noted that the stop-ears 17-17 of the body-member 10 prevent the gripping-member 11 from being displaced off from the upper end of the body-member 10 in the direction of the slot 16, after the said body-member 10, the gripping-member 11 and the strap 24 have been assembled as above described. For the purpose of guarding against the displacement of the gripping-member 11 off from the lower end of the body-member 10, each of the side-walls 13-13 of the said body-member is provided adjacent its lower end with one of two stop-bosses 28-28.

After the slide-buckle parts 10 and 11 have been assembled with each other and with the strap 24 as above described, any downward draft upon the running-portion 25 of the strap 24 will cause the gripping-member 11 to also move downwardly. This downward movement of the gripping-member 11 will cause the same to move rearwardly relative to the body-member 10 by virtue of the engagement of the cam-surfaces 22-22 with the camming-surfaces 14-14 of the side-walls 13-13 of the said body-member 10. This rearward movement of the gripping-member 11 as just described, will cause the gripping-bar 19 thereof to pinch the running-portion 25 of the strap 24 against the flutes 15 of the front-panel 12 of the body-member 10, thus firmly holding the said running-portion 25 against further downward movement.

This gripping action of the gripping-member 11 as above described, will cause the said gripping-member to shift from substantially the position in which it is shown by broken lines in Fig. 4 to the position in which it is shown by full lines in the same figure.

To effect the release of the running-portion 25 of the strap 24 the gripping-member 11 may

be directly grasped and moved upwardly from substantially the position in which it is shown by full lines in Fig. 4 to substantially the position in which it is shown by broken lines in the 5 same figure to thereby cause the said gripping-member to ride along the camming-surfaces 14-14 of the body-member 10 in the general direction of the slot 16 and permit the gripping-bar 19 to retire further away from the front-panel 12 of the body-member 10.

By providing a gripping-member having both a gripping-bar and a strap-attaching bar respectively located adjacent the front and rear surfaces of a body-member, such as the body-member 10 above described, and attaching one 10 end of a strap to the said strap-attaching bar, downward tension upon the looped lower portion of the said strap extending below the buckle structure acts through the intermediary of both 15 of the aforesaid bars to more firmly grip the running-portion of the strap against the front face of the body-member 10 or its equivalent.

Furthermore, by means of the structure of the 20 present invention, the fixed-portion of a strap 25 may be conveniently and expeditiously attached to the gripping-member prior to the assembly of the said gripping-member with a complementary body-member.

The invention may be carried out in other 25 specific ways than those herein set forth without departing from the spirit and essential characteristics of the invention, and the present embodiments are, therefore, to be considered in all respects as illustrative and not restrictive, 30 and all changes coming within the meaning and equivalency range of the appended claims are intended to be embraced therein.

I claim:

1. A slide-buckle assembly including in combination: a body-member having a front-panel for gripping-engagement with the running-portion of a strap and having a transverse strap-receiving slot in its upper portion, the said body-member also including two longitudinally-tapered side-flanges respectively projecting rearwardly from the opposite sides of the said front-panel and having their rear faces each providing a rearwardly-facing camming-surface inclined downwardly and rearwardly away from the strap-receiving slot in the said body-member in a direction longitudinally thereof; a gripping-member of loop-like form having a gripping-bar extending transversely across the front face of the front-panel of the said body-member and a strap-attaching bar extending across the rear of the said body-member in engagement with the inclined rear edges of the said side-flanges thereof, the said gripping-member also including two side-bars interconnecting the said gripping-bar and the said strap-attaching bar, and the median planes of said side-bars, gripping-bar and strap-attaching bar in a direction substantially at right angles to said front-panel, substantially lying in a common plane; and a strap having an end looped around and attached to the strap-attaching bar, and said strap depending from the strap-attaching bar of the said gripping-member and reversely looped and having a running-portion extending upwardly between the front face of the front-panel of the said body-member and the gripping-bar of the said gripping-member and also extending upwardly and then rearwardly through the strap-receiving slot in the upper portion of the said body-member.

2. A slide-buckle including in combination: a body-member having a front-panel for gripping-engagement with the running-portion of a strap and having a transverse strap-receiving slot in its upper portion, the said body-member also including two longitudinally-tapered side-flanges respectively projecting rearwardly from the opposite sides of the said front-panel and having their rear faces each providing a rearwardly-facing camming-surface inclined downwardly and rearwardly away from the strap-receiving slot in the said body-member in a direction longitudinally thereof; and a gripping-member of loop-like form having a gripping-bar ex-

tending transversely across the front face of the front-panel of the said body-member and a strap-attaching bar extending across the rear of the said body-member in engagement with the inclined rear edges of the said side flanges thereof, the said gripping-member also including two side-bars interconnecting the said gripping-bar and the said strap-attaching bar, and the median planes of said side-bars, gripping-bar and strap-attaching bar in a direction substantially at right angles to said front-panel, substantially lying in a common plane.
